(57) **CLAIM**

The ornamental design for a door mat with simulated woven border, as shown and described.

DESCRIPTION

FIG. 1 is a top view of a door mat with simulated woven border showing my new design;

FIG. 2 is a bottom view thereof, shown to be plain and unornamented;

FIG. 3 is an enlarged fragmentary perspective top view thereof;

FIG. 4 is a front view thereof; the unshown opposite rear view being of identical appearance;

FIG. 5 is a side view thereof; the unshown opposite side view being of identical appearance; and,

FIG. 6 is an enlarged sectional view thereof taken in the direction of the arrows upon the line 6—6 of FIG. 1.
